(57) CLAIM

The ornamental design for a vehicle, as shown and described.

DESCRIPTION

FIG. 1 is a perspective view of a vehicle in accordance with an embodiment of the present invention;

FIG. 2 is a side view of the vehicle shown in FIG. 1;

FIG. 3 is a front view of the vehicle shown in FIG. 1;

FIG. 4 is a rear view of the vehicle shown in FIG. 1; and,

FIG. 5 is a top view of the vehicle shown in FIG. 1.

The bottom view of the vehicle is not part of the claimed design. The broken lines, including for the tail lamp, the rear view mirrors, styling lines on the bumpers, and the door handles, illustrate the environment of the design and are not part of the claimed design.

1 Claim, 4 Drawing Sheets
